HOISTING APPARATUS

Ernest W. Holmes, Chattanooga, Tenn.; S. Bartow Strang, administrator of said Ernest W. Holmes, deceased, assignor to Ernest Holmes Company, Chattanooga, Tenn., a corporation of Tennessee

Application March 27, 1944, Serial No. 528,314

20 Claims. (Cl. 212—59)

1

The present invention relates to improvements in hoisting apparatus, and more especially to wreckers of the type employed for handling disabled automotive and other vehicles and for other uses where hoisting, pulling, towing or similar operations are to be performed.

One of the primary objects of the invention is to provide novel and improved operating and controlling mechanism for the cable winding drums whereby the construction thereof is simplified and improved and the operation thereof is facilitated.

Another object is to provide novel and improved driving mechanism for the cable winding drums of apparatus of this character, and particularly wreckers, of the double boom type in which each boom has a drum for the boom cable and a drum for the hoisting or service cable, whereby one or more or all of the drums may be operated at any time under control of a single attendant and from a single power drive.

Another object of the present invention is to provide novel and improved hoisting apparatus which, when mounted on a wrecking truck or other vehicle, is readily accessible as to all of its parts for inspection or servicing.

Another object is to provide a novel and improved frame in which the mechanism of the hoisting apparatus is accommodated compactly and which enables narrow hoisting drums of large diameter to be used, with the advantage that fewer layers of cable require to be wound thereon for a cable of given length than heretofore, and thereby avoiding or minimizing wedging of the cable between convolutions of a lower layer thereof, as frequently takes place in winding a large number of layers of a tensioned cable upon a drum, the frame being so designed that such narrow large diameter drums may be readily removed edgewise therefrom, should such become necessary for servicing or other purposes.

Further objects of the invention are to provide a novel and improved construction of driving mechanism for the cable drums which facilitates the manufacture thereof, minimizes stresses thereon under load, enables the parts thereof to be readily removed for servicing or other purposes, and which is otherwise well adapted to meet all of the requirements of heavy-duty apparatus of this type.

To these and other ends, the invention consists in certain improvements, and combinations and arrangements of parts, all as will be hereinafter more fully described, the features of

2

novelty being pointed out more particularly in the claims at the end of this specification.

In the accompanying drawings,

Figure 1 is a side elevation of the improved hoisting apparatus according to the present invention, the same being shown mounted on a truck and adapted to be employed as a wrecker;

Figure 2 is a top plan view of a portion of the apparatus shown in Figure 1;

Figures 3 and 3^a are collectively a rear elevation of the apparatus on an enlarged scale, the booms being shown as swung from the opposite sides of the truck;

Figure 4 is a detail view of one of the slings for the upper ends of the booms;

Figure 5 is a detail view in vertical section of the driving gearing for the boom and service cables of one of the booms;

Figure 6 is an elevation of the gearing as viewed from the right in Figure 5;

Figure 7 is a detail horizontal section taken on the line 7—7 in Figure 6;

Figure 8 is an elevation of the transfer or transmission mechanism through which the driving gearings for the booms and the service cables are driven;

Figure 9 is a plan view of the transfer mechanism, with the cover thereof removed and parts shown in section;

Figure 10 is a section taken on the line 10—10 in Figure 8;

Figure 11 is an enlarged detail elevation of the lower portion of one side of the frame, showing the drums for the service and boom cables;

Figure 12 is a rear elevation of the structure shown in Fig. 11, with the drum operating means;

Figure 13 is a detail section showing the swivel mounting of the service sheave in the upper end of the boom;

Figure 14 is a detail view showing the manner of attaching the sling to the sheave yoke at the upper end of the boom;

Figures 15 and 16 are detail sectional views showing the mountings of the swivels for the boom cable guide sheave and the boom respectively; and

Figure 17 is a detail horizontal section on the line 17—17 in Fig. 11.

Similar parts are designated by the same reference characters in the several figures.

The hoisting apparatus, according to the present invention, comprises a frame 1, a pair of swinging booms 2, and cable winding drums and driving mechanism therefor which form a complete unit. As shown in Figure 1, this unit is

adapted to be mounted on the chassis 3 of a motor truck so that the frame of the hoisting apparatus extends transversely of the truck immediately behind the driver's cab 4, all of the parts of the hoisting mechanism being readily accessible from the rear and sides of the frame, as will hereinafter appear.

The frame 1 comprises a pair of parallel, spaced vertical columns 5 at each side, each column being composed preferably of channel iron, a pair of horizontal base members 6, also preferably composed of channel iron, to the outer sides of which the lower ends of the columns 5 are riveted, welded or otherwise fixed and a similar pair of horizontal members 7 connecting the respective columns 5 and similarly fixed thereto. Angle irons 8 extend horizontally between and connect the tops and diagonal braces 9 connect the ends of the upper angle irons and plates 10 riveted, welded or otherwise fixed to the lower portions of the columns 5. The frame is supported rigidly on the truck chassis.

The booms 2 are each pivoted on a horizontal pivot 11 carried by a swivel 12 having a vertical stem 13 fitted rotatably in upper and lower plates 14 bolted, welded or otherwise fixed to the top and bottom respectively of the base members 6 spanning the space between them, the booms being thus mounted to swing upwardly and downwardly about the horizontal pivot 11 and to swing laterally about the vertical stem 13 as an axis. The upper end of each boom is provided with a sheave 15 over which the hoisting or service cable 16 passes, this cable being equipped at its end with a hook 17 or other suitable means for engaging it with an automobile or other vehicle or object to be hoisted or hauled, the sheave being journaled on a horizontal shaft 18 in a yoke 19 swiveled in the upper end of the boom, a cable guide 19^a being connected to this yoke for causing it to swivel in the end of the boom when a load is being pulled from either side thereof. The upper end of each boom is also equipped with means for attaching a boom cable thereto for raising and lowering it. The boom cable 20 is attached at one end by a pin 21 to a sheave carrier 22, the latter being pivoted by the horizontal pin 23 to a swivel 24, the latter having a hollow vertical stem 25 which is mounted rotatably in plates 26 which span the spaces between and are bolted, riveted, welded or otherwise fixed to the tops of the angle irons 8 and the upper and lower edges of the channel irons 7. Each sheave carrier has a sheave 27 journaled therein, around which the boom cable passes, the boom cable also passing around a pair of sheaves 28 journaled on a pin 29 in a yoke 30.

The present invention provides novel means for attaching the boom cable yoke 30 to the upper end of the boom whereby the load on the boom will be distributed and sustained equally at opposite sides of the service sheave 15, and such attaching means will avoid fouling with the upper end of the boom when the latter is raised. Such attaching means comprises a yoke 31 which is hooked by its intermediate portion in the yoke 30 and carries a pair of sheaves 32 which are journaled on a pin 33 in the yoke 31. The sheaves 32 are connected to the upper end of the boom by a sling composed of a suitable length of flexible cable 34 the ends of which are connected to form a loop, the intermediate portions of the loop being passed around the respective sheaves 32 and the ends of the loop being passed around grooved segmental bosses 35 on the outer sides of

the yoke 19, the pivot pin 18 for the service sheave passing through these bosses and being removable without disturbing the support of the boom by the sling. Clamps 36 are preferably employed to bind together the ends of the loop adjacent to the sheave pin 18. By this arrangement, the load on the boom is divided between and sustained by the ends of the sling at opposite sides of the service sheave, and the portions of the load sustained by the ends of the sling are equalized by the sheaves 32, especially when the yoke 19 swivels in the upper end of the boom, as takes place while the service cable is pulling a load from a side of the boom, thus equalizing the tension on all of the boom supporting cables. The ends of the sling straddle the upper end of the boom as the latter is raised, as shown in Figure 3^a, thus avoiding interference with the raising of the boom to its extreme height. An outrigger leg 40 is preferably provided for supporting the load on one or the other side of the frame while the boom at that side of the frame is swung laterally from the truck to lift a load at a side thereof. Each of these legs, as shown, comprises a pair of telescopic sections 41 and 42 adapted to be held adjusted to different lengths by a pin 43 which may be inserted through holes in the section 41 and the appropriate pair of opposite holes 44 spaced longitudinally of the section 42. The lower section of the leg is provided with a foot 42^a to bear on the ground when the leg is extended laterally of the truck and the section 42 lowered. The upper section of the leg is pivoted on a horizontal pin 45 in a swivel 46 and the latter is provided with a vertical stem or journal which is rotatable in plates 26 and 26^a spanning the space between and secured to the frame members 7. The universal pivoting of the legs 40 to the frame enables each leg to be extended at any angle laterally from the truck, as shown in Figure 3, to bring it beneath the respective boom and sustain a side pull or load, spreading of the lower end of the leg being prevented by a chain 47 which may be attached to the lower end of the leg and one of the base members of the frame, and when the leg is not in use it may be folded against a side of the truck, as shown in Figure 3^a, and locked by a spring plunger 48.

The service cable extends from the boom sheave 15 over a sheave 50 journaled in a swivel 51 having a hollow vertical stem 52 rotatably mounted in a pair of the plates 26 of the frame, this cable passing through the stem 52 and winding on a hoisting or service drum 55. The boom cable passes from one of the sheaves 28 over a sheave 57 and downwardly through the respective swivel stem 25, then around a guide sheave 58 and winds on a drum 59.

Each service cable drum 55 is of relatively large diameter and of relatively short axial length, thus enabling a given length of cable to be wound thereon with a fewer number of layers of the cable than is possible with a drum of relatively small diameter, thus avoiding tendency of the service cable, while under load, to become wedged between convolutions of an underlying layer, and the narrow dimension of the drum enables it to be accommodated between the upright columns 5 at the respective sides of the frame. This drum 55 is mounted to rotate on or with a shaft 56 supported in bearings 60 in the relatively fixed plates 10 and from which it is removable axially, and the drum 55 carries a driving gear 61 which meshes with a pinion 62 loose-

ly mounted on a driving shaft 63 and is coupled thereto by splines 163 and a clutch collar 163^a slidable thereon, the shaft 63 being journaled in bearings 64 supported by the plates 10, and being removably retained in said bearings by a plate 63^a secured to the end of the shaft 63 by a cap screw 63^b. A band brake 65 is preferably provided for controlling the slack in the service cable, this brake extending partly around the gear 61 and being drawn into frictional engagement with it by a tension spring 66, one end of which is attached to the frame and the other end of which is connected to an arm 67 fixed to and projecting radially from a shaft 68, the latter being mounted rotatably in the columns 5 of the frame and having a yoke 69 fixed thereon and connected to one end of the brake band 65, the other end of this band being connected at 70 to a suitable part of the frame. A loop 71 extends radially from the shaft 68 and is urged toward the portion of the service cable between the drum and the sheave 50. While the service cable is under tension, as while a load is thereon or this cable is being pulled to unwind it from the drum, it will engage or swing the loop 71 to rotate the shaft 68 against the action of the spring 66 and in a direction to release the brake band 65 from the gear 61 and thus avoid a drag upon the drum during lifting or lowering a load or while the service cable is being pulled manually from the drum, but as soon as the service cable becomes slack, the loop 71 deflects the cable under the action of the spring 66 and the latter rotates the shaft 68 in a direction to frictionally engage the brake band 65 with the periphery of the gear 61, thus avoiding over-running of the drum and consequent disarrangement of the cable thereon.

The drum 59 for winding the boom cable is removably mounted, by splines 59^a, on a shaft 75 which is journaled in bearings 76 supported by the relatively fixed frame plates 10, and removably retained therein by a plate 76^a secured to the end of the shaft 75 by a cap screw 75^a.

The pinion shaft 63 for driving the service cable drum and the shaft 75 on which the boom cable drum is splined extend rearwardly from the frame and have worm wheels 77 and 78 respectively keyed or otherwise removably fixed thereon for driving them in relatively opposite directions to wind the cables on the respective drums 55 and 59. According to the present invention, the worm wheel 77 meshes with a worm 79 keyed or otherwise fixed on a shaft 80, and the worm wheel 78 meshes with a worm 81 keyed or otherwise fixed on a shaft 82 adjacent and parallel to the shaft 80. The worm shafts 80 and 82, which are driven in relatively opposite directions, are mounted in bearings 83 which sustain the radial and axial loads on these shafts, these bearings being preferably of the annular ball bearing type and mounted removably in a casing 84 which contains or encloses the worm wheels 77 and 78, this casing having bearings 85 in which the shafts 63 and 75 carrying the worm wheels are journaled. By so mounting the worm shafts in the casing and providing the casing with bearings for the worm wheel shafts, the casing and worm shafts are supported on or suspended from the worm wheel shafts independently of the main frame 1, and by removably mounting the drum 59 on the shaft 75 and removably mounting the pinion 62 on the shaft 63, the casing 84 together with the worm gearing therein can be removed as a unit after the plates 63^a and 76^a have been removed and the torque screws 96 and

97 loosened, for inspection or repair of these units or adjacent parts in the frame. As the cable winding drum is mounted rotatably on the shaft 56 and the latter is removable axially from its bearings in the plates 10, this drum may be readily removed edgewise from the adjacent side of the frame after removal of its shaft. The torque reaction between the casing 84 and the worm wheel 77 or 78 while being driven by its respective worm is sustained by thrust screws 96 and 97 which are adjustable in brackets 98 and 99 fixed to the rear side of the main frame, these screws being adjusted to bear against the respective ends of the casing 84, although, while both worm wheels are being driven simultaneously, the torque reaction upon the casing 84 in one direction will neutralize the torque reaction thereon in the other direction, due to the opposite directions of rotation of the worm wheels 77 and 78.

The casing 84 is preferably composed of a pair of duplicate halves 84^a and 84^b united by flanges 86 which may be bolted together, as shown, this design of the casing enabling a single pattern to be used for both and otherwise facilitating the manufacture thereof. The bearings 83 for the worm shafts are removable axially, thus enabling the worm shafts and the worms thereon, which are of smaller diameter than the bearings, to be removed axially from the casing for servicing or replacement. The bearings 83 are retained in the casing by end plates 87 which are bolted or otherwise removably secured thereon, these end plates sustaining the end thrust of the worms. In order to prevent unintentional lowering of the boom or unwinding of the service cable, due to tendency of the worm gearing to back off under a load, because of the low resistance of the anti-friction bearings for the worms, each of the worm shafts 80 and 82 which operate the service and boom cable drums 55 and 59 respectively is preferably provided with a friction brake which will prevent unwinding of the service or boom cable from its respective drum, but will not interfere with the normal lifting and lowering operations of these cables. Each friction brake comprises, in the present instance, a friction cone 90 which is keyed on the respective worm shaft and abuts against a shoulder 91 thereon, and an outer cone 92 which is movable axially on the worm shaft and is urged against the cone 90 by a compressed coil spring 93 which encircles the worm shaft. The periphery of the outer cone 92 is provided with a pair of axially extending ribs 94 between which a pin 95 threaded into the casing projects, this pin and the ribs permitting axial movement of the outer cone 92 but preventing rotation thereof, whereby the reaction of the frictional braking torque applied to the worm shaft by the inner cone 90 will be sustained.

The present invention provides novel and improved transfer or transmission mechanism whereby power may be applied to either service or boom drum or to any number or all of these drums, as may be desired. Such mechanism, as shown in the present instance, comprises pairs of axially aligned shafts 100 and 101 journaled in bearings 102 and 103 respectively, which are bolted or otherwise rigidly fixed in the opposite side walls of a casing 104 having a removable cover 104^a. The outer ends of the shafts 100 are connected by couplings 106 to the worm shafts 80 which drive the drums 55 for the service cables for the respective booms, and the outer ends of

the shafts 101 are connected by couplings 107 to the worm shafts 82 which drive the drums 59 for the boom cables for the respective booms. The inner ends of the shafts 100 have jaw clutch members 108 and 109 splined thereon to shift axially although connected to rotate therewith, and the inner ends of the shafts 101 have similar jaw clutch members 110 and 111 splined thereon to shift axially although connected to rotate therewith. A shaft 112 is interposed between the inner ends of the shafts 101 in axial alignment therewith, the ends of this shaft being reduced and journaled rotatably in the inner ends of the shafts 101, and the shaft 112 has a jaw clutch member 113 and a gear 114 keyed or otherwise fixed thereon, the gear 114 having jaw clutch teeth 115 fixed thereon, the clutch member 113 and clutch teeth 115 being companions to the clutch members 110 and 111 respectively, and being engageable thereby to connect the shaft 112 to the respective shafts 101. A shaft 116 similar to the shaft 112 is interposed between the inner ends of the shafts 100 in axial alignment therewith, and has reduced ends journaled rotatably in the inner ends of the shafts 100, and the shaft 116 has a jaw clutch member 117 and a gear 118 keyed or otherwise fixed thereon, the gear 118 having clutch teeth 119 thereon, the clutch member 117 and the clutch teeth on the gear 118 being companions to the clutch members 108 and 109 respectively, and being engageable thereby to connect the shaft 116 to the respective shafts 100. Power is applied to the shaft 112 by a shaft 120 which is journaled in a bearing 121 bolted or otherwise fixed in an end wall of the casing 104, the shafts 112 and 120 being connected by bevel gears 122 and 123 keyed or otherwise fixed to the respective shafts, and the gears 114 and 118 fixed on the shafts 112 and 116 mesh with one another whereby the shaft 116 is driven from the shaft 112 but in the opposite direction of rotation. The shaft 120 preferably receives power for rotating it in one or the other direction for lifting or lowering operations from any suitable or well known form of power take-off from the usual truck engine, as, for example, from a sprocket wheel 124 driven in one or the other direction by any usual or conventional form of reversible power take-off from the transmission 125 of the truck, a chain 126 driven from said sprocket wheel, and a sprocket wheel 127 fixed to the shaft 120.

The four jaw clutches thus provided in the transfer mechanism enable any one or more or all of the shafts 100 and 101 to be driven by power from the single power shaft 120, and means is provided for controlling these clutches from a remote point, preferably the cab of the truck. Such controlling means, as shown in the present instance, comprises a set of Bowden wires 131, 132, 133 and 134, the outer tubes or casings of which are held, as by a clamp 135, on the top of the casing 104 and the inner wires of which extend into the cab where they are connected to levers, knobs or other appropriate control members within convenient reach of an attendant in the cab. The other ends of the wires are operatively connected to levers 136, 137, 138 and 139 above the cover 104a of the casing 104, these levers being fixed to the upper ends of shafts 140, 141, 142 and 143, respectively, journaled in suitable bearings in the casing 104. The shafts 140, 141, 142 and 143 have forks 144, 145, 146 and 147, respectively, fixed thereon, these forks cooperating with grooved collars on the

sliding clutch members 108, 109, 110 and 111, respectively, whereby rotation of each shaft in one or the other direction by pulling or pushing its respective Bowden wire will slide the respective sliding clutch member into or out of engagement with its companion clutch member. Means is preferably provided for yieldingly retaining each sliding clutch member in engaged or disengaged position, such means, in the present instance, comprising a bowed spring 148 pivotally connected at one end to a hook 149 fixed in the adjacent end of the casing 104 and pivotally connected at its other end to a pin 150 fixed in the respective clutch shifting fork. The spring 148 normally tends to contract or close, thereby biasing the pin 150 on the respective clutch shifting fork in a direction toward the hook 149, and the hook 149 and pin 150 are so located on opposite sides of the respective clutch shifting shaft that the pin 150 will move to one or the other side of a dead center position as the respective shifter fork is rotated to engage or disengage the respective sliding clutch member, each spring thus serving to yieldingly retain the respective sliding clutch member in engaged or disengaged position.

The transfer mechanism, as shown, is so designed that its mechanism may be readily removed from the casing 104 for servicing or other purposes. The bearings 102 and 103 are bolted or otherwise removably fitted in the opposite sides of the casing, and by removing these bearings and their shafts, the latter are withdrawn from the ends of the shafts 112 and 116, thereby releasing these latter shafts for removal freely through the open top of the casing 104 while the cover 104a thereof is removed. As the sliding clutch members are splined removably on the inner ends of the shafts 100 and 101, they also are readily removable from the open top of the casing. The axial thrust on the shaft 112 from the bevel gear 122 is sustained by an anti-friction thrust bearing 155 which abuts at one side against the inner end of the respective bearing 103 and at its other end against a shoulder 156 on the respective shaft 101, and this shaft contains an anti-friction thrust bearing 157 against which the adjacent end of the shaft 112 abuts whereby the axial thrust from the bevel gear 122 is transferred from the shaft 112 to the respective shaft 101 and from the latter through the bearing 155 to the adjacent bearing 103. The axial thrust of the other bevel gear 123 is sustained by the inner end of the bearing 121 through an anti-friction thrust bearing 158 which is interposed between its inner end and the gear 123. Oil seals 159 are provided for the shafts 100 and 101 whereby an oil bath may be maintained in the casing 104 and leakage therefrom prevented.

In some instances, it may be desirable to tie together the upper or free ends of the booms and thus provide a rigid structure and the hoisting, towing, pulling or hauling may be done conjointly by both booms, one of the booms being provided for such purposes with an apertured ear 160 projecting from a side thereof and the other boom with a socket 161 to receive said ear when the booms are brought together, a spring actuated locking pin 162 being carried by the socket and engageable in the aperture of the ear, substantially like the boom locking arrangement disclosed in my prior Patent Reissue No. 14,720, granted September 2, 1919.

The construction and operation of the various elements of the apparatus having been described

in detail, the general operation of the complete apparatus is as follows: Normally, or while the apparatus is in transit, both booms are preferably swung to the rear of the truck and tied together by the locking pin 162, unintentional unwinding of the service or boom cables from their drums under the influence of the load being prevented by the friction brakes 93, 92 on the shafts of the worms which drive the service and boom cable drums 55 and 59.

The hoisting, towing, pulling, hauling or other operations may be performed either while the booms are tied together and sustain the load conjointly, or such operations may be performed by either or both of the booms operating separately, as while one boom is being employed to hoist, pull, haul or otherwise operate upon a load sustained by one of the booms while swung to one side of the truck while the other boom is swung to the other side of the truck and its service cable is attached to an anchor so that this service cable acts as a guy for the other boom which sustains the load.

Assuming the booms have been arranged appropriately for the operation to be performed, the power take-off from the transmission of the truck will be put into operation for lifting, the power shaft 120 being thereby driven continuously in the appropriate direction by power taken from the usual engine of the truck. In order to lift one or the other boom, the Bowden wire 133 or 134 is pulled, thereby shifting the respective sliding clutch member 110 or 111 to couple the shaft 112 to the respective shaft 101, in consequence of which the respective worm 81 will drive its cooperating worm wheel 78 in a direction to rotate the boom operating drum 59 in a direction to wind the respective boom lifting cable 20 thereon, thus lifting the respective boom, and when such boom reaches the desired height, the clutch member which was engaged will be disengaged from its companion clutch member by pushing the respective Bowden wire 133 or 134, thus stopping the boom lifting operation, and the boom will be held in its adjusted position by the irreversible action of the respective worm 81 and cooperating worm wheel 78; or when both booms are to be raised simultaneously, both clutch members 110 and 111 are engaged at the same time.

After the boom employed for hoisting, pulling, hauling or similar operation has been thus adjusted to the desired height or angle, the appropriate Bowden wire 131 or 132 is pulled, thereby shifting the respective sliding clutch member 108 or 109 into engaged position and thereby coupling the shaft 116 to the respective shaft 100, causing operation of such shaft to drive the respective worm 79 and thereby drive its cooperating worm wheel 77 in a direction to rotate the drum 55 to wind the service cable 16 thereon. Since the load to be lifted or pulled is attached to the hook 17 on the service cable, the load will be lifted or pulled until the respective clutch member 108 or 109 is disengaged from its companion clutch member by pushing the respective Bowden wire 131 or 132, whereupon the lifting or pulling of the load will be stopped, and the load will be supported by the irreversible action of the respective worm 79 and worm wheel 77. When both service cables are employed at the same time for hoisting, pulling or similar operations, both clutch members 108 and 109 are engaged at the same time by simultaneously pulling both Bowden wires 131 and 132.

In some instances, it may be desired to lift

75

either or both booms and operate either or both service for lifting at the same time, in which event, it is merely necessary to pull the appropriate ones or all of the Bowden wires, all of the power for these operations being provided by the single power shaft 120.

In order to lower one or the other boom or to lower the service cable to which the load is attached, the power take-off from the truck transmission is reversed or set to drive the shaft 120 in the opposite direction to that for lifting, and the sliding clutch member corresponding to the boom or service cable to be lowered is engaged with its companion clutch member by pulling the respective Bowden wire, thereby causing power to be taken from the shaft 120 to rotate the respective worm and cooperating worm wheel to rotate the corresponding boom drum or service drum in a direction to unwind the respective boom or service cable, and, obviously, one or more or all of the boom and service drums may be driven simultaneously, if desired, the power therefor being supplied from the single power shaft 120.

The torque reaction between the worm wheel 77 or 78 and the casing 84 will be sustained by the stops or adjustable screws 96 and 97 which abut against the ends of the respective casing 84, although when both worm wheels 77 and 78 are driven simultaneously to raise the respective boom and lift or pull a load on the service cable for that boom, the torque reaction on the casing 84 from one worm will be neutralized more or less by the torque reaction from the other worm wheel, it being noted that the worm wheels 77 and 78 are driven in opposite directions to wind the cables on the drums 55 and 59, respectively.

Also, as the axial thrusts of the worms 79 and 81 are in opposite directions during their operation to raise the boom and lift the service cable, the reactions of such axial thrusts are distributed between the opposite sides of the casing 84, thus enabling this casing to be constructed of relatively light weight, and the torque sustaining screws for this casing may also be of relatively light weight. As each casing 84 is mounted on the respective worm wheel shafts 63 and 75 and may each be removed as a unit therewith as hereinbefore described, these units and also the rear side of the frame in the region in which the drums 55 and 59 are located are readily made accessible.

The large diameter service drums 55 employed not only enable a sufficient length of service cable to be wound thereon in a minimum number of layers, thus avoiding wedging of the cable between the convolutions of the layers wound on the drum under tension of the load, but also enable drums which are relatively narrow or of short axial length to be employed. Such narrow drums may be accommodated in a narrow frame which may be conveniently mounted transversely on a truck immediately behind the cab, thus rendering the rear side of the frame accessible for servicing of the mechanism therein and leaving the rest of the truck body available for loading or other purposes, and the narrow service drums, as well as the boom operating drums 59, may be readily removed edge wise from the respective ends of the frame, after removal of their shafts, for servicing or other purposes.

The employment of worms and worm wheels for driving the service and boom winding drums greatly simplifies the apparatus since these worms and worm wheels are irreversible, that is, the worms will hold the worm wheels against retrograde rotation under the loads imposed upon the

11

service and boom winding drums, and will automatically hold the load and the boom at any height to which the same are lifted, thereby obviating the necessity of employing complicated ratchets for locking the drums, and releasing and controlling means for unwinding the cables from the drums, as heretofore. Also, the present invention provides a novel transfer mechanism whereby the power for driving the drums to both wind and unwind the service and boom cables may be derived from a single power shaft which may be driven conveniently by the usual engine of the truck on which the apparatus is mounted.

The present invention provides a heavy duty apparatus of great power and strength for performing efficiently and rapidly a variety of operations, such as lifting, pulling, hauling or towing disabled automobiles or other vehicles or apparatus, in which all of the power required is supplied from a single source and may be controlled conveniently, as from the cab of a truck, and the various parts of the apparatus are readily accessible for inspection, removal or other servicing.

I claim as my invention:

1. Hoisting apparatus comprising a frame, a boom mounted thereon, service and boom operating cables cooperative with the boom, drums for winding the respective cables, shafts mounted on the frame and connected to the respective drums for driving them, a worm wheel fixed to each of said shafts, a casing supported directly by said shafts independently of the frame, worms mounted in said casing and cooperative with the respective worm wheels for operating them, and means on the frame and cooperative with said casing for sustaining the torque reaction of said worm wheels thereon.

2. Hoisting apparatus according to claim 1, wherein said torque reaction sustaining means comprises abutment members on the frame engaging opposite portions of said casing.

3. Hoisting apparatus according to claim 1, wherein said torque reaction sustaining means comprises a pair of aligned screws mounted on the frame and adjustable into abutting relation with opposite portions of said casing.

4. Hoisting apparatus according to claim 1, wherein said worm wheels rotate in relatively opposite directions to operate the respective drums to wind the cables thereon.

5. Hoisting apparatus according to claim 1, wherein said worms are mounted in parallel relation in said casing and rotate said worm wheels in relatively opposite directions to wind the respective cables thereon, and means for sustaining the thrust of said worms against the respective ends of said casing.

6. Hoisting apparatus comprising a pair of booms, service and boom operating cables for each boom, drums for winding the respective cables, gearings individual to said drums for the respective booms for operating them, a power shaft, and transfer mechanism interposed between said gearings and driven by said power shaft and comprising clutches for individually connecting the power shaft to the respective gearings for selectively operating the service and boom cable drums for both booms from said power shaft.

7. Hoisting apparatus according to claim 6, wherein said transfer mechanism comprises a pair of shafts, gearing connecting them to rotate in relatively reverse directions, one of said shafts being connected to said power shaft to be driven thereby, clutch members on said pair of shafts,

5 companion clutch members connected respectively to said gearings, and means individual to said clutch members and companion clutch members for engaging and disengaging them.

8. Hoisting apparatus according to claim 6, wherein said transfer mechanism includes means for each of said clutches for yieldingly holding the same in engaged and disengaged conditions.

9. Hoisting apparatus comprising a boom, service and boom operating cables cooperative therewith, drums for winding and unwinding the respective cables, worm wheels disposed in different but adjacent planes and connected to the respective drums for operating them, a casing composed of similar halves enclosing the respective worm wheels, and a pair of worms journaled in the ends of the respective casing halves in adjacent parallel relation and engaging the respective worm wheels.

10. Hoisting apparatus comprising a frame, a pair of booms mounted thereon, service and boom operating cables cooperative with the respective booms, drums mounted in the frame for winding and unwinding the cables, gearing including worm wheels connected to the drums for each boom and a pair of worms meshing respectively with the worm wheels for the respective boom, transfer mechanism comprising a casing, a power shaft journaled therein, a pair of driving shafts connected to the power shaft and provided with clutch members, pairs of driven shafts journaled in the opposite sides of the casing in alignment with and supporting the respective driving shafts and having sliding clutch members on their inner ends to cooperate with the respective clutch members on said driven shafts, said driven shafts being connected to the respective worms, clutch shifting means in the casing for operating said sliding clutch members, and means exteriorly of the casing and connected to said clutch shifting means for operating the same.

11. Hoisting apparatus comprising a frame adapted to be mounted transversely on a truck and having parallel upright columns providing openings at the opposite ends of the frame and at the respective sides of the truck, booms swiveled on the frame adjacent to its opposite ends, service and boom operating cables cooperative with each boom and extending into the respective ends of the frame, drums for winding said cables movable edgewise into and out of operative positions between the columns through said openings at the respective ends of the frame, and shafts mounted in the frame for removably supporting the drums therein for rotation in a common plane.

12. Wrecking apparatus for mounting on a truck transversely and behind the cab thereof, comprising a relatively narrow frame having drums mounted in a common plane in each end thereof at the respective side of the truck for winding a service cable and a boom operating cable, a boom swiveled on a vertical axis adjacent to each end of the frame and cooperative with said service and boom operating cables, sets of gearings at a side of the frame and adjacent to the respective ends thereof for operating the drums for the service cable and boom operating cable for the respective booms, and transfer mechanism mounted at said side of the frame midway between its ends and between said sets of gearings and connected to said sets of gearings for operating them.

13. In hoisting apparatus, a boom, a sheave

for a service cable swiveled in the end of the boom for rotation about the longitudinal axis of the boom as a center, a boom operating cable, a supporting sheave having a shaft connected to the boom operating cable, and a sling having its ends connected to the outer end of the boom at opposite sides of said sheave, and having a portion thereof between its ends extending around said supporting sheave connected to the boom operating cable.

14. In hoisting apparatus, a boom having a sheave mounting swiveled in the end thereof for rotation about the longitudinal axis of the boom as a center, a service cable sheave supported by said mounting for rotation on a substantially horizontal axis, a boom supporting cable, a pair of supporting sheaves having a shaft connected to said cable, and a sling having its ends looped and engaging the sheave mounting at opposite sides of the service cable sheave, and having its intermediate portions extended around said pair of supporting sheaves.

15. Hoisting apparatus comprising a boom, service and boom operating cables cooperative therewith, drums for winding the respective cables, worm and worm wheels connected to the respective drums for rotating them to wind and unwind the respective cables, power means for operating the worms, and a friction brake cooperative with each worm for holding it against rotation independently of the power means, said friction brake comprising inner and outer conical members, one of which is fixed to turn with the respective worm, and means including a pin cooperative with the other conical member to permit axial movement but prevent rotation thereof.

16. Hoisting apparatus comprising a narrow elongated frame, a pair of booms mounted respectively on the ends thereof, service and boom operating cables for each boom, drums mounted in the respective ends of the frame for winding the respective cables, gearings adjacent to the respective ends of the frame and individual to said drums for operating them, a power shaft mounted between the ends of the frame, and transfer mechanism mounted adjacent to and driven by said power shaft and comprising clutches for individually connecting the power shaft to the respective gearings, and means connected to said clutches for controlling them from a remote point.

17. Hoisting apparatus comprising a frame, a boom pivotally mounted thereon, a service cable carried by the boom, a boom supporting cable connected to the boom, a pair of drums mounted in said frame adjacent to the pivotal mounting of the boom for winding the respective cables, a casing adjacent to the pivotal mounting of the boom, a pair of worm wheels mounted in the casing and connected respectively to said drums, a pair of worms mounted in the casing and cooperating respectively with the worm wheels, a power shaft, means operable by the power shaft

for rotating said worms in relatively opposite directions to operate the drums to wind the respective cables, and clutches between the power shaft and said worms for selectively connecting the latter to the power shaft.

18. Hoisting apparatus comprising a frame, a boom pivotally mounted thereon, a service cable carried by the boom, a boom supporting cable connected to the boom, a pair of drums mounted in the frame adjacent to the pivotal mounting of the boom for winding the respective cables, a casing adjacent to the pivotal mounting of the boom, a pair of worm wheels mounted in the casing in overlapping relation and in adjacently located planes, a gear connected to one of the worm wheels and cooperative with one of the drums, a shaft connected to the other of said worm wheels and connected directly to the other drum, said gear and shaft rotating the drums in the same cable winding direction by rotation of the worm wheels in relatively opposite directions, a pair of worms mounted in said casing and meshing with the respective worm wheels, a power shaft, and worm driving shafts having means for connecting them to the power shaft to rotate the worm wheels in relatively opposite directions to wind the cables on the respective drums.

19. Hoisting apparatus comprising a frame, a pair of booms pivotally mounted at opposite ends thereof, service cables carried respectively by the booms, boom lifting cables for the respective booms, service and boom cable operating drums mounted in the respective ends of the frame adjacent to the pivotal mountings of the respective booms thereon, a pair of gearings at a side and adjacent to the respective ends of the frame and connected to the respective adjacent drums for operating the drums, a power shaft mounted intermediately between the ends of the frame, pairs of shafts extending longitudinally at said side of the frame, means for connecting the shafts of each pair respectively to the gearings for operating the service and boom cable drums adjacent to the respective ends of the frame, and means including clutches for selectively connecting the shafts of said pairs to the power shaft.

20. Hoisting apparatus comprising a boom, service and boom operating cables cooperative therewith, drums for winding the respective cables, worm wheels disposed in different but adjacent planes and connected to the respective drums for rotating them to wind and unwind the respective cables, worms mounted on adjacent parallel axes and cooperating with the respective worm wheels, power means for operating the worms, clutches for connecting and disconnecting the worms and power means, and friction brakes constantly acting on the respective worms to resist rotation thereof and thereby hold them against rotation under the influence of the respective worm wheels while the worms are disconnected from the power means.

ERNEST W. HOLMES.
